STOKER CONTROL SYSTEM

Harry G. Manson and Robert P. Hansen, Princeton, Ind., assignors to Hansen Manufacturing Company, Princeton, Ind., a corporation of Indiana

Original application May 10, 1948, Serial No. 26,058. Divided and this application March 25, 1949, Serial No. 83,418

9 Claims. (Cl. 236—46.)

1
This invention relates to control switches, and particularly to devices of this type especially adapted for use in controlling stokers and similar mechanisms.

This application is a division of application of Harry G. Manson and Robert P. Hansen, Serial No. 26,058, filed May 10, 1948, resulting in U. S. Letters Patent No. 2,542,824, dated February 20, 1951.

Most automatic stoker controls include an overall controlling portion which selects between normal daytime stoker operation and nighttime operation which is generally of a reduced-fire nature.

Such controls also usually include, and ordinarily as an entirely separate mechanism, instrumentalities for effecting reduced-fire operation of the stoker during the night period.

A reduced-fire control of this type consists of means for intermittently energizing the stoker drive motor so that the fire which the stoker is feeding is maintained at some predetermined burning rate which prevents the fire from going out during the night and which may also, especially in severe weather, provide sufficient heat units to maintain the building being heated at a certain temperature.

As mentioned before, stoker controls of this type generally include the two sections identified above and which are generally separately constructed, although often placed in a single frame to be sold as a unit.

The present invention has as its primary object the construction of a stoker control arrangement which is truly unitary in character in that it employs only a single driving motor.

Another object of this invention is to provide an improved stoker control which is very convenient to adjust at any time.

It is also an object of this invention to provide a stoker control including a time switch having a driven part which is engaged and disengaged from the driving motor in order to make it selectively effective or ineffective.

A still further object is the provision of a stoker control device which is connected with building thermostats and the like and which operates over a 24-hour period to control a stoker through normal and reduced-firing operations.

These and other objects and advantages will become more apparent upon reference to the following description taken in connection with the accompanying drawings in which:

Figure 1 is a front elevational view showing a control switch constructed according to this invention;

2
Figure 2 is a view looking at the switch in the same direction as Figure 1 but with the front cover of the switch removed in order to show the various gear trains and other devices;

5 Figure 3 is a vertical section indicated by the lines 3—3 on Figures 1 and 2;

Figure 4 is a vertical section indicated by the lines 4—4 on Figures 1 and 2;

10 Figure 5 is a plan section indicated by the lines 5—5 on Figures 1 and 2;

Figure 6 is a plan section indicated by the lines 6—6 on Figures 1 and 2;

Figure 7 is a sectional view indicated by the lines 7—7 on Figures 5 and 6;

15 Figure 8 is a vertical section indicated by the lines 8—8 on Figures 1 and 2; and

Figure 9 is a wiring diagram showing how the switch of this invention could be connected in circuit with a stoker motor and suitable thermostatic switches for controlling the operation of a stoker.

Referring to the drawings, the device of this invention comprises a frame or box-like enclosure 10, and formed thereon, as at 12, is a dial inscribed with numerals for indicating the hour and whether it be a. m. or p. m. A pointer 14 sweeps over the said dial and an adjusting knob 16 may be provided for correcting the position of the pointer 14 should the indicating position thereof be incorrect.

Adjacent the stationary dial 12 is a pair of other similarly inscribed dials 18 and 20, said dials being rotatable and geared to the pointer 14 to rotate in unison therewith. Associated with each of the dials 18 and 20 is a pointer 22 adjustably connected therewith and adapted for normally rotating with the said dials. These pointers are adjustable to indicate certain times of the day at which the device effects controlling adjustments in the stoker motor operating circuits.

Also mounted on the frame 10 is a reduced-fire or cycling arrangement 24 including a dial 26 over which is movable a pointer 28. The device 24, as will become apparent hereinafter, is the reduced-fire part of the stoker control and is operable for intermittently energizing the stoker drive motor and for predetermined periods of time thereby to maintain the fire at a reduced rate during the night or during any other period that the building being warmed would not have to be kept up to full temperature.

The drive arrangement for the pointer 14 and the dials 18 and 20 is best illustrated in Figures 2 and 3. In these figures it will be seen that the frame 10 mounts a synchronous electric drive

motor 30 which carries a pinion 32. The pinion 32 runs on a gear 34 which is mounted on a shaft with another pinion 36. The pinion 36 in turn drives through a gear 38 which is mounted on the same shaft as the pinion 40. The pinion 40 drives into a gear 42 which is frictionally connected with the shaft 44 that supports the adjusting knob 16 referred to above.

Pinned to the shaft 44 is another drive gear 46 and meshing with the gear 46 is a gear 48 carried on the shaft 50 which drives the pointer 14. Also meshing with the gear 46 is a gear 52 which is the same size as the gear 48 and which is connected with the dial 20. A gear 54 of the same size as the gears 48 and 52 also meshes with the gear 46 and is connected for driving the dial 18. The connections between the gears 52 and 54 and their respective dials 18 and 20 is best illustrated in Figure 6 wherein it will be seen that each of the said gears has a sleeve part and on the end of which is mounted the associated dial.

The frictional connection of the gear 42 with the shaft 44 permits the simultaneous adjustment of the pointer 14 and the dials 18 and 20 in order to correct for the position thereof when the clock has been stopped due to the power being shut off or for some other reason. Normally, the frictional connection between the gear 42 and the shaft 44 is effected by the spring washer indicated at 43 and is sufficient for maintaining a driving connection between the said gear and shaft.

Each of the pointers 22 is connected with its corresponding dial 18 or 20 by means of a spring pressed clutch portion indicated at 56. The pointers are squared to fit over the square portions 58 of the shafts 60 and there is thus normally effected a driving engagement between the shafts and the dials. However, when the pointers are adjusted relative to the dials by pulling the pointers out against their loading springs and turning them, the said shafts rotate with the pointers while the dials remain stationary.

Attached to the shafts 60, that are within the recess 62 formed in the back wall of the frame 10, are a pair of cam wheels 64 each of which carries a cam member 66 adapted for engagement with a snap action switch mechanism indicated at 68. This switch mechanism will be best seen in Figures 6 and 7, and it will be apparent that it comprises a toggle mechanism including an arm having a roller 70 at the end thereof which will be in a leftward position after the switch has been actuated by the cam 66 associated with the dial 18, and in a rightward position after the switch has been actuated by the cam 66 associated with the dial 20. The switch proper, associated with the toggle switch arrangement, includes a movable contact 72 which closes on a stationary contact 74 when the roller is in its leftward position, and which closes on a contact 76 when the roller is in its rightward position.

As explained above, each of the cam wheels 64 can be adjusted relative to its driving disc and thereby accurately controls the time of day when the switch mechanism 68 will be actuated by the cams carried by the said cam wheels. Thus, over a period of 24 hours, the switch mechanism at 68 will first be actuated into one position by one of the cam wheels and then into another position by the other of the cam wheels.

The aforementioned switch arrangement is for the purpose of selecting between daytime and nighttime operation of the stoker. During the

daytime, as will be seen hereinafter, the control of the stoker is effected by a thermostatic switch located in the building being heated. During nighttime operation, the operation of the stoker is controlled by a reduced-fire mechanism which intermittently energizes the stoker motor for predetermined periods of time.

The reduced-fire portion of the stoker control of this invention is best seen in Figures 2 and 4. This part of the stoker control comprises a frame or bracket 78 which is mounted for free swinging movement about a shaft 80 extending through the back wall of the frame or housing 10.

Mounted in the bracket 78 is a gear train comprising a gear 82 pinned to the shaft 80, a pinion 84 meshing with the gear 82 and a gear 86 rigidly mounted with the pinion 84. The shaft 80 also has mounted thereon an arm 88 and positioned in the rotative path of the arm 88 is a pair of spaced stops 90 and 92 carried by the bracket 78.

The stop 90 is angularly adjustable relative to the bracket 78 by means of a knob 94 which is rigidly connected with the stop 90 and which may provide support for the inner end of the shaft 80 as at 96.

A spring washer 98 provides frictional engagement between the stop member 90 and the bracket 78 so that when the said stop member is positioned by turning the knob 94, it will thereafter remain in that position relative to the bracket 78 until again moved by the said knob.

Reference to Figure 2 will reveal that extending downwardly from the bottom of the bracket 78 is a rod 100 which extends through a slot 102 in a plate 104 pivoted on a screw 106, see Fig. 4. A spring 108 bears between the plate 104 and the bottom of the bracket 78 and provides for a toggle action of the bracket as it moves about the shaft 80, thus snapping it sharply into its two operative positions.

The extreme positions to which the bracket 78 will move are determined by the slot 102 in plate 104 and the stops 110 positioned one on each side of plate 104 and predetermining the limits of movement thereof.

When the bracket 78 is in its full line Figure 2 position, the gear 86 meshes with an idler pinion 112 mounted on the back of the housing 10 and which is adapted for being driven through a gear train including the gears 114, 116, 118 and pinion 120 by the gear 38. When the bracket 78 is in its other operative position, as shown in dot-dash outline in Figure 2, the gear 86 is spaced from the pinion 112 and is thus not driven thereby.

Movement of the bracket 78 into its full line Figure 2 position is accomplished by a torsion spring 122 connected between the shaft 80 and the back wall of the housing 10. This spring acts through the shaft 80 and arm 88 against stop 90 and rotates the bracket 78 counterclockwise. Thereafter, the bracket 78 is moved into its other position by the engagement of the arm 88 with the stop 92.

The driving of the gear train in the bracket 78 exerts a thrust on the stop 90 which snaps the bracket into its dot-dash position in Figure 2. It will be noted that at that time the spring 122 is operative to drive the gear train and the arm 88 back to their starting positions, thus to bring about movement of the bracket 78 back to its full line Figure 2 position and reengagement of the gear 86 and pinion 112.

Mounted about the shaft 80 is a cam plate 124

having a pin 126 therein which is adapted for engaging the bifurcated end 128 of one arm of the toggle-action switch 130.

It will be apparent that clockwise movement of the cam plate 124 will effect closing of the contact 132 of the switch 130 whereas counter-clockwise movement of the said cam plate will open the said contacts. The cam plate is retained in frictional driving engagement with the shaft 80 by means of the disc 134 and the spring washer 136. The cam plate is further adjustable relative to the said disc by means of the screw and slot arrangement 138.

The operation of the reduced-fire portion of the stoker control is as follows:

Assuming the bracket 78 to be moved to its Figure 2 position, the gear 86 will be driven through the pinion 112 and gear 82, driven by pinion 84, will drive the shaft 80, thereby driving the disc 134 and cam plate 124 in a clockwise direction.

After a predetermined time, the pin 126 carried by the cam plate will engage and trip the toggle switch 130 into closed position. Thereafter, the said switch will remain closed during continuous clockwise movement of the cam plate. Rotation of the cam plate and gearing in the bracket 78 will continue until the arm 88 engages the stop 92. At that time the bracket 78 will be snapped into its dot-dash Figure 2 position.

The spring 122 now drives the gearing in the bracket 78, the cam plate and the arm 88 backwardly, and during this retracting movement of the cam plate the switch 130 will again be tripped into its open position. When the arm 88 has moved to the point where it engages the stop 90, it will again shift the bracket 78 into its Figure 2 position, and a new cycle will commence.

It will be apparent that the length of time that the switch 130 is closed will be determined by the location of the cam plate 124 relative to the disc 134 and that the overall period, including both the closed and open periods, for the switch 130 will be determined by the spacing of the stops 90 and 92.

During normal daytime operation of the stoker it is not desired to use the reduced-fire feature, and to this end, the bracket 104 has a rod 140 projecting therefrom which is adapted for engagement with the plunger 142 of a solenoid 144. Energization of the solenoid 144 will move the plunger 142 rightwardly and thrust the bracket 104 in a direction to hold the bracket 78 in its dot-dash Figure 2 position.

The switches and the solenoid referred to above are connected in circuit with a stoker motor as shown in Figure 9. In Figure 9 the timing motor 39 is connected between the power lines L1 and L2 and in series with an on-off selector switch 146. The power line L1 is also connected by a wire 148 with the movable contact 72 of the switching device 68. The contact 76 of this switching device is connected by a wire 150 with one side of a normally open thermostatic switch 152, the other side of which is connected by a wire 154 with one terminal of the solenoid 144.

The other side of the solenoid 144 is connected by a wire 156 with the power line L2. The other contact 74 of the switching device 68 is connected by a wire 158 with the wire 154 and also by a wire 160 with one side of the thermostatic switch 162, the other side of which is connected by a wire 164 with one side of a relay coil 166.

The other side of the relay coil 166 is con-

nected with the power line L2. The relay is operable, when energized, to move its blade 168 into position to complete a circuit between the lines L1 and L2 and through the stoker motor indicated at 170. The end of the coil 166 connected with the wire 164 is also connected by a wire 172 with one of the contacts 132, the other of which is connected by a wire 174 with the power line L1.

The thermostatic switch 152 referred to above is normally open below a predetermined temperature and closed above the said temperature, whereas the thermostatic switch 162 is normally closed below a predetermined temperature and opens above that temperature. The switch 162 is for the purpose of effecting normal daytime control of the stoker motor relay coil 166, whereas the switch 152 becomes effective for nighttime operation and controls the effectiveness of the cycling reduced-fire arrangement which includes the toggle switch 130.

Operation

The operation of the stoker control unit of this invention is briefly as follows:

The stoker motor is connected in circuit with the control unit, the stoker motor, control relay, and the control thermostats as shown in Figure 9.

It will be understood that other suitable and well known thermostatic control elements could be added to the circuit as it is desired, as, for example, a stack control to prevent the fire bed from overheating, or other elements designed to detect certain temperatures and translate them into control impulses.

The unit having been connected in circuit with the stoker motor and the controlling thermostats, the pointers 22 are set relative to their respective dials 18 and 20 to select the times at which normal daytime operations of the stoker motor begin and end.

The beginning of the time operation will be determined by the setting of the pointer 22 associated with the dial 18, and this pointer and dial arrangement is operative to throw the switch mechanism at 68 into the position shown in Figure 9 wherein the contact member 72 closes on the contact 74.

At this time the thermostatic switch 162 is connected in series with the relay coil 166, and a circuit is also completed through the solenoid actuator 144 which throws the reduced-fire cycling control out of engagement with the drive motor. Under these conditions, the relay coil 166 is energized or de-energized as determined by the thermostatic switch 162.

When the temperature of the building being heated by the stoker controlled furnace reaches a predetermined temperature, the switch 162 opens and the relay coil 166 is de-energized and, in turn, de-energizes the stoker motor 170. As mentioned before, the control circuit for the relay coil 166 can include stack controls, low water controls, and other control devices that are well known in the art, if desired.

At the end of a normal daytime operating cycle the switch mechanism 68 is engaged by the cam associated with the dial and pointer 20, 22, and is shifted into position to close the contact member 72 on the contact 76. At this time the thermostatic switch 162 is cut out of the circuit and loses its control over the relay coil 166. The circuit through the solenoid actuator 144 is also interrupted, and its control over the reduced-fire cycling control is also lost.

As explained before, with the solenoid actuator 144 de-energized, the torsion spring 122 will shift the swinging bracket 78 into position to bring the gears 112 and 86 into engagement. This commences a timing cycle which will determine the length of time that the toggle switch 132 will be closed. This switch is in series with the relay coil 166 and thus determines a period of energization for the said relay coil and thereafter of the stoker motor 170. Normally, this period of energization of the stoker motor is a matter of a few minutes every half hour or hour, depending upon the average outside temperature and the requirements of the building being heated, and, in general, is well known in the stoker art.

Normally, the reduced-fire cycling control will continue to operate unless the temperature of the building being warmed reaches a predetermined amount, at which time the thermostatic switch at 152 will close and will complete a circuit through the solenoid actuator 144 which will throw the reduced-fire cycling control into inoperative position, thus permitting the relay coil 166 and stoker motor 170 to remain de-energized until the building temperature is again reduced to permit the thermostatic switch 152 to open.

Normally, the thermostatic switch 152 is set to open at a lower temperature than that at which the switch 162 will close, and preferably both of the thermostatic switches are adjustable according to well known practices.

After a predetermined period of operation under the cycling reduced-fire control, the cam associated with the pointer and dial 18, 22, will again become effective to move the switch mechanism 68 into its Figure 9 position, and the stoker control will again operate on a normal daytime cycle.

It will be understood that this invention is susceptible to modification in order to adapt it to different usages and conditions, and accordingly, it is desired to comprehend such modifications within this invention as may fall within the scope of the appended claims.

We claim:

1. In a stoker control; a stoker motor control relay, a thermostatic switch for controlling said relay during the normal firing operations, a reduced-fire control comprising a switch which closes at intervals to control said relay, a second thermostatic switch for controlling said reduced-fire control, and a time switch operable to make said first thermostatic switch and reduced-fire control alternatively effective for controlling said relay.

2. In a stoker control; a stoker motor control relay, a thermostatic switch for controlling said relay during the normal firing operations, a reduced-fire control comprising a switch which closes at intervals to control said relay, a second thermostatic switch for controlling said reduced-fire control, a time switch operable to make said first thermostatic switch and reduced-fire control alternatively effective for controlling said relay, and a single synchronous electric motor connected to drive said time switch and said reduced-fire control.

3. In a stoker control; a stoker motor, a relay energizable to energize the stoker motor, a first thermostatic switch responsive to the temperature of the enclosure being heated for energizing said relay when the temperature falls below a predetermined amount and for de-energizing said relay when the temperature rises above a pre-

determined amount, a cycle switch connected with said relay operable for periodically energizing said relay for a predetermined length of time for reduced-fire operation of the stoker, a second 5 thermostatic switch responsive to the temperature of the enclosure being heated for making said cycle switch ineffective for energizing said relay when the temperature rises above a predetermined amount and effective for energizing 10 said relay when said temperature falls below a predetermined amount, a two-position control switch connected in circuit with said thermostatic switches and having one position wherein one thermostatic switch is effective for controlling 15 said relay and a second position wherein the other of the thermostatic switches is effective for controlling said cycle switch, and a synchronous motor and cam means driven by said motor for alternately actuating said two-position switch into 20 its two operative positions so the said switch occupies one position for a part of a twenty-four-hour period and its other position for the remainder of the twenty-four-hour period, and said motor being operable to effect actuation of said cycle switch during the period of effectiveness of the cycle switch.

4. In a stoker control; a stoker motor, a relay energizable to energize the stoker motor, a first thermostatic switch responsive to the temperature of the enclosure being heated for energizing said relay when the temperature falls below a predetermined amount and for de-energizing said relay when the temperature rises above a predetermined amount, a cycle switch connected with said relay operable for periodically energizing said relay for a predetermined length of time for reduced-fire operation of the stoker, a second thermostatic switch responsive to the temperature of the enclosure being heated for making said cycle switch ineffective for energizing said relay when the temperature rises above a predetermined amount and effective for energizing said relay when said temperature falls below a predetermined amount, a two-position control 45 switch connected in circuit with said thermostatic switches and having one position wherein one thermostatic switch is effective for controlling said relay and a second position wherein the other of the thermostatic switches is effective for controlling said cycle switch, and a synchronous motor and cam means driven by said motor for alternately actuating said two position switch into its two operative positions and for actuating said cycle switch, said cam means being adjustable to predetermine the hours of the day said two-position switch will be in each of its two positions.

5. In a stoker control; a stoker motor, a relay energizable to energize the stoker motor, a first thermostatic switch responsive to the temperature of the enclosure being heated for energizing said relay when the temperature falls below a predetermined amount and for de-energizing said relay when the temperature rises above a predetermined amount, a cycle switch connected with said relay operable for periodically energizing said relay for a predetermined length of time for reduced-fire operation of the stoker, a second thermostatic switch responsive to the temperature of the enclosure being heated for making said cycle switch ineffective for energizing said relay when the temperature rises above a predetermined amount and effective for energizing said relay when said temperature falls below a predetermined amount, a two-position control switch

connected in circuit with said thermostatic switches and having one position wherein said first switch is effective for controlling said relay and a second position wherein said second switch is effective for controlling said cycle switch, a synchronous motor, a cycle cam for said cycle switch geared to said motor, other cams connected with said motor for controlling said two-position switch, and electrical means controlled by said second thermostatic switch for disconnecting said cycle cam from said motor.

6. In a stoker control; a stoker motor, a control relay for said motor, a first thermostatic switch and a cycle switch in parallel and connected in series with said relay, a two-position switch having a first position wherein said thermostatic switch is effective for controlling said relay and a second position wherein said cycle switch is effective for controlling said relay, electrical means energizable to make said cycle switch ineffective for controlling said relay, a second thermostatic switch for energizing said electrical means, and means responsive to movement of said two-position switch into its first position for energizing said electrical means.

7. In a stoker control; a stoker motor, a relay for controlling the energization of said motor, a first thermostatic switch and a cycle switch in parallel and connected in series with said relay, a two-position switch having a first position wherein said thermostatic switch is effective for controlling said relay and a second position wherein said cycle switch is effective for controlling said relay, electrical means energizable to make said cycle switch ineffective for controlling said relay, a second thermostatic switch for energizing said electrical means, means responsive to movement of said two-position switch into its first position for energizing said electrical means, and a synchronous motor and cam means driven by said motor for controlling said two-position switch and said cycle switch.

8. In a stoker control; a stoker motor, a control relay for said motor, a first thermostatic switch and a cycle switch in parallel and connected in series with said relay, a two-position switch having a first position wherein said thermostatic switch is effective for controlling said relay and a second position wherein said cycle switch is ef-

fective for controlling said relay, electrical means energizable to make said cycle switch ineffective for controlling said relay, a second thermostatic switch for energizing said electrical means, means responsive to movement of said two-position switch into its first position for energizing said electrical means, and a synchronous motor and cam means driven by said motor for controlling said two-position switch and said cycle switch, said cam means being adjustable for predetermining the periods of operation of said switches.

9. In a stoker control; a stoker motor, a control relay for said motor, a first thermostatic switch and a cycle switch in parallel and connected in series with said relay, a two-position switch having a first position wherein said thermostatic switch is effective for controlling said relay and a second position wherein said cycle switch is effective for controlling said relay, electrical means energizable to make said cycle switch ineffective for controlling said relay, a second thermostatic switch for energizing said electrical means, means responsive to movement of said two-position switch into its first position for energizing said electrical means, a synchronous motor, first cam means connected with said motor for alternately moving said two-position switch into its two operative positions, second cam means connected with said motor for controlling said cycle switch, said electrical means being operative when energized for disconnecting said second cam means from said motor.
